UNITED STATES PATENT OFFICE.

WILLIAM F. CAPITAIN, OF CHICAGO, ILLINOIS, ASSIGNOR TO MARDER,
LUSE & CO., OF SAME PLACE.

DESIGN FOR TYPE.

SPECIFICATION forming part of Design No. 18,508, dated August 7, 1888.

Application filed June 15, 1888. Serial No. 277,267. Term of patent 7 years.

To all whom it may concern:

Be it known that I, WILLIAM F. CAPITAIN, a citizen of the United States of America, residing at Chicago, in the county of Cook and 5 State of Illinois, have invented a certain new and original Design for a Font of Printing Type, of which the following is a specification, reference being had therein to the accompanying typographical impressions.

10 My invention relates to a new design for a font of printing-type consisting of heavy capital and lower-case letters, numerals, and points.

15 The leading feature of the said design consists in the letters having the thin and thick portions of their lines flowing together irregularly and unsteadily, all as hereinafter fully described, and as shown in the typographical impressions and claimed.

20 A consists of a heavy front inclined line, a comparatively light back inclined line, a middle straight heavy horizontal line joined to the inclined lines, a lower ornamental line connected with the front line near its base and slightly inclined downward and then enlarged 25 and extended upward, connecting with the lower end of the back line and terminating with a downward curve, and a curved line connected with the upper portion of the back line and extended and curved backward and 30 downward and enlarged at its termination.

The lower ends of the back vertical lines of B and R and the vertical stems of F and I terminate in backwardly-inclined points, and the letter B is provided with a central line connected with the meeting-point of the front 35 double curves of the letter, and this central line is extended backward across the vertical line and is slightly enlarged toward the end and terminates in an upward curve. The

40 lower portion of this letter B is ornamented with a line enlarged at its connection with the lower front curve and is extended upward and backward, nearly touching the point of the vertical line, and terminates with a downward and 45 forward curve, being diminished at its curve and enlarged at its termination.

The upper front portion of C, F, and S is enlarged at the end and gradually diminished backward, giving it the appearance of a 50 snake's head and neck.

The back line of D is heavy in its middle portion, is diminished gradually toward each end, and is slightly curved backward at the bottom and forward at the top. The top, front, and bottom portions of the letter consist of a curved line extended at the top slightly above and back of the point of the back line, and the lower portion of this curved line is abruptly curved upward, forming a downwardly-extended point, and the line is then extended backward, touching the lower point of the back line and terminating in a fine point in the rear of the back line of the letter.

55 The inner central portion of E, consisting of a line connected with the inner edge of the body of the letter, has its back portion curved slightly downward and its front portion curved slightly upward, and has its middle portion enlarged.

60 The middle portion of F consists of a line commencing in front of the stem with a heavy end inclined slightly downward, and the line is thence extended backward and obliquely downward across and terminating back of the 75 stem, the entire letter having the appearance of a lower-case letter f made with a coarse pen.

70 The capital letter H is made in the shape of a lower-case h, the back line being enlarged 80 slightly at the ends, which terminate in upwardly-inclined edges, the upper end extending slightly above the upper part of the front curved portion, which extends below the lower end of the back line and terminates with a forwardly-extended foot-shaped base.

75 The vertical stem of I is rounded at the top, and this stem and the stem of J are each provided with two straight lines connected with the stems and extended backward obliquely 90 upward and downward to a meeting-point in the form of the lines of a triangle.

The top of I and of Z consists of a backwardly-extended line, heavy at the back end, and provided with a fine point inclined obliquely downward, the front portion of the said lines terminating near the top of the stems in fine upwardly-curved points.

95 The top of J consists of a slightly-curved line connected with the top of the stem and 100

(over)

extended and enlarged backward and then diminished abruptly to a fine point, and the lower portion of the stem of this letter is curved slightly forward and is provided with 5 a backwardly-extended base-line inclined slightly downward.

The ends of the back vertical line of K terminate in fine points inclined upward and forward at the top and downward and forward at 10 the bottom, and these ends are provided with short reversely-curved ornamental lines, the upper ornament nearly touching the upper end and the lower ornament connecting with the lower point of the back line.

15 The back lines of the capitals M, N, V, and W and the lower-case v and w are curved backward and extended above the other portions of these letters, and the back, middle, and front portions of M are connected together 20 near the bottom by short heavy lines. The back line of N extends below the front line and terminates in a backwardly-extended curved base-line, and the front lines of this letter and of U terminate in forwardly-extending curved base-lines, these base-lines being enlarged toward their terminal ends.

The lower portion of P is curved backward and upward, and is slightly diminished at the curve and enlarged at its termination, and the 30 other portion of this letter is formed by the continuation of the stem curved forward, downward, and backward, and it extends across and terminates back of the stem in a slightly downward curve.

35 The upper portion of R is provided with an ornamental line connected with the top of the stem and curved backward and downward and slightly enlarged toward its termination.

The stem of T and back line of U are heavy 40 in the middle portions and diminished and curved forward toward the upper and lower ends. The head of T is heavy in its middle portion, which nearly touches the upper end of the stem, and diminishes toward both ends, 45 the back portion being curved downward and the front portion being curved upward, and both terminating in slight rounded enlargements.

A short slightly-curved line is connected 50 with the upper portion of the back line of U, and is enlarged and extended backward. The upper portion of the front line of this letter is curved slightly forward.

The two lines of V v and the three main lines 55 of W w are all curved backward both at the top and bottom, and all the parts of W are connected together at the top by straight oblique lines and at the bottom by the continuation of the curved lines.

The upper portion of the lower-case d is 60 curved backward and upward, and the curved line, which is a continuation of the stem and forms the body of the letter, approaches nearly to but does not touch the stem.

The lower portion of f terminates in a downwardly-extended point, and the middle of this letter is provided with a straight oblique transverse line, downwardly inclined in front.

The top of g is provided with a straight horizontal line extended backward beyond the 70 body of the letter, and the tail of the letter is curved forward, downward, backward, slightly upward, and then downward and forward, terminating in a fine point.

The lower portion of the front part of h is 75 curved slightly backward, and is extended below the back line of the letter, and terminates in a short forwardly-extended base-line.

The lower portion of j is inclined slightly backward, and is slightly diminished at its 80 termination.

The back portions of h, k, and p, the body of i, l, m, n, and t, and the front line of q and the numeral 1 consist of vertical straight lines of uniform thickness, the upper portions of 85 the lines of m and n being inclined backward and all connected together.

The upper portion of the back line of y is inclined slightly backward, and its tail is formed by the continuation of this back line, 90 which is inclined slightly backward and then curved forward and upward, terminating in a downward curve, and the front portion of the body of this letter consists of a loop formed by a line connected with the back line below its 95 upper end, and extended thence obliquely upward on a straight line, and then bent abruptly downward and curved backward and connected with the said back line at the backward inclination of the tail of the letter.

100

What I claim as new is—

The new design for a font of printing-type, the leading feature of the design consisting in the letters having the thin and thick portions of their lines flowing together irregularly and 105 unsteadily, and the shape of the letters and other portions of the font being as herein described and as shown in the typographical impressions.

In testimony whereof I have affixed my signature in presence of two witnesses.

WILLIAM F. CAPITAIN.
